United States Patent Office.

GARDNER CHILSON, OF BOSTON, MASSACHUSETTS.

Letters Patent No. 76,302, dated April 7, 1868.

IMPROVEMENT IN STOVE-GRATES.

The Schedule referred to in these Letters Patent and making part of the same.

TO ALL PERSONS TO WHOM THESE PRESENTS MAY COME:

Be it known that I, GARDNER CHILSON, of Boston, in the county of Suffolk, and State of Massachusetts, have made a new and useful invention having reference to Grates for Stoves or Furnaces; and I do hereby declare the same to be fully described in the following specification, and represented in the accompanying drawings, of which—

Figure 1 is a top view,
Figure 2 a front elevation,
Figure 3 a longitudinal and vertical section.
Figure 4 a transverse section, and
Figure 5 a horizontal section of the base portion of a hot-air furnace with my invention applied thereto.
Figure 6 is a top view, and
Figure 7 a side elevation of the grate-shaft head.
Figure 8 is a top view,
Figure 9 an under side view, and
Figure 10 a longitudinal section of the handle to be applied to the grate-shaft, for either moving it laterally or for revolving it, as circumstances may require.

In the drawings, A denotes the ash-chamber part of the furnace-base, and B the throat thereof. C is the grate, which has a journal, a, at its centre, to rest upon a forked bracket or projection, D, and between the prongs b b thereof, such bracket D being projected from the inner curved surface of the base, A. The grate is constructed of two concentric annuli, c d, a series of parallel bars e e e, and a series of teeth f f f, the latter being extended radially from the entire circumference of the larger annulus, the whole being as represented in the drawings. The grate, so made, has a shaft, E, extended from it, in line with its journal, and through a bearing, g, in a plate or shoulder, h, which is curved with a radius whose centre is at the centre of the grate. The said plate h should be supported so as to be capable of being moved horizontally in either direction. It constitutes a cover to a slot, i, made in the front plate k of the throat of the ash-chamber, the grate-shaft being extended through such slot. The grate-shaft is provided with a head, l, formed with projections r r, as represented in figs. 6 and 7. A handle, H, shown in figs. 8, 9, and 10, may be used with the grate-shaft, such handle being constructed not only with a socket, o, to receive the shaft-head, but with claws or hooks p p, to catch thereupon, so as to enable the grate-shaft to be either revolved or shaken laterally, the claws holding the handle to the shaft when such handle is either vertical or horizontal.

By revolving the grate-shaft ninety degrees, the grate will be turned, so as to discharge into the ash-chamber any coals which may be on the grate; so, by moving the grate-shaft back and forth laterally, reciprocating rotary movements will be imparted to the grate for the purpose of discharging ashes through the spaces between its grate-bars. When in a horizontal position, the grate rests on a projection, l', extended from the wall of the ash-chamber. The prongs of the bracket D are formed as shown in top view in fig. 1, in order to allow of the horizontal vibration of the grate.

The furcated bracket may extend up from the bottom of the ash-chamber, but in such case it would be in the way of a shovel or other implement, when used in clearing the chamber of ashes or cinders. By arranging it so as to project horizontally, or thereabouts, from the wall of the ash-chamber, and immediately under the grate, such bracket will be out of the way of a shovel or other implement when used to remove ashes from the ash-chamber.

I am aware that a bar with a swivel-loop for the grate has been used; also that a cross-bar, having a furcated projection at its centre, to provide for oscillating and dumping the grate, has been in use. These I do not claim; but

What I claim as my invention, and desire to secure by Letters Patent, is—

The furcated arm D, for supporting the grate, arranged so as to allow both the tilting and lateral vibration thereof, substantially as herein specified.

Also, the grate-shaft head and handle, made substantially as represented, and as hereinbefore described.

GARDNER CHILSON.
